(57) **CLAIM**

The ornamental design for a shellfish tool, as shown and described.

DESCRIPTION

FIG. 1 is a perspective view of a first embodiment of a shellfish tool showing my new design;

FIG. 2 is a top view thereof;

FIG. 3 is a bottom view thereof;

FIG. 4 is a side view thereof;

FIG. 5 is an opposite side view thereof;

FIG. 6 is a front view thereof;

FIG. 7 is a rear view thereof; and,

FIG. 8 is a perspective view of a second embodiment of a shellfish tool showing my new design wherein the wire portion is longer.
